UNITED STATES PATENT OFFICE.

WILLIAM W. WALKER, OF CAMDEN, NEW JERSEY, ASSIGNOR TO MACANDREWS & FORBES COMPANY, OF CAMDEN, NEW JERSEY, A CORPORATION OF NEW JERSEY.

PORTABLE FIRE-EXTINGUISHER.

1,186,250.

Specification of Letters Patent. Patented June 6, 1916.

Application filed September 2, 1915. Serial No. 48,592.

To all whom it may concern:

Be it known that I, WILLIAM W. WALKER, a citizen of the United States, residing at Camden, in the county of Camden and State of New Jersey, have invented new and useful Improvements in Portable Fire-Extinguishers, of which the following is a specification.

This invention relates to portable fire-extinguishing apparatus.

The apparatus is intended to use two separate liquids or solutions which, when mixed together, operate to produce foam and a gas noxious to combustion.

15 A principal object of the invention is to provide a simple portable apparatus for carrying the two liquids and for projecting the mixture of the liquids toward the flames.

20 A further object of the invention is to provide, in a fire-extinguishing apparatus, a simple and efficient construction of mixing chamber in which the separate liquids or solutions are brought together to produce a foam, the said mixing chamber including 25 in its construction a 3-way valve to the outlet opening of which a hose may be attached for directing the foam toward the fire, the construction providing a readily operable means for quickly producing the foam when 30 desired.

35 Another object of the invention is to provide a portable fire-extinguishing apparatus of the type referred to with means for maintaining a substantially uniform reduced air pressure in the separate containers of the apparatus in which foam-producing liquids are stored, and which liquids are to be forced from the containers by air pressure therein supplied thereto from a high 40 pressure air reservoir carried by the apparatus.

45 A further object of the invention is to provide a container having a construction especially adapting it to sustain internal pressure, and to construct and arrange the apparatus so as to avoid the necessity for using flat plates where employed in the construction of the container.

50 Further objects of the invention will appear more fully hereinafter.

The invention consists in the general combination of parts and details described herein, all of which contribute to produce an efficient portable fire extinguisher.

55 A preferred embodiment of the invention

is described in the following specification, while the broad scope of the invention is pointed out in the appended claims.

In the drawing, Figure 1 is a plan of apparatus embodying my invention, certain parts being broken away. Fig. 2 is a longitudinal vertical section taken substantially on the line 2-2 of Fig. 1. Fig. 3 is a rear elevation of the apparatus. Fig. 4 is a horizontal cross-section through the mixing device or mixer in which the liquids mix before they are finally projected toward the fire. Fig. 5 is a vertical section through a reducing valve which is embodied in the invention.

70 The apparatus preferably embodies a frame 10 of simple form mounted upon wheels 11 and provided with a shaft 12 which enables the frame to be pushed from place to place. The frame is suitably supported on an axle 13 to which the wheels are attached and this axle is preferably formed with a downwardly extending bow 14 near its middle portion to conform to the shape of the duplex container. The liquids 75 which are used in the apparatus are preferably held in separate containers.

According to my invention, I provide 80 means for developing air pressure in the containers so as to force the liquids out and I effect the mixture of the liquids and project the mixture toward the fire. In order 85 to accomplish this I prefer to provide two containers 15 which are preferably formed in a cylinder 16 which cylinder is carried in 90 a substantially horizontal position on the frame. This cylinder is provided with convex preferably substantially hemispherical heads 17 and is divided into two containers 15 by means of a transverse partition or bulk head 18, constructed of a flat plate.

The upper side of the cylinder 16 is provided with two removable closures 19 which give access to the interior of the two containers 15 to enable them to be supplied with 95 their respective liquids. The cylinder 16 is preferably supported from underneath by transverse straps or girths 20, the ends of which are attached on the side bars 21 of the frame. The hemispherical shell form of the heads 17 is very advantageous as this form of head withstands a high internal pressure without bulging or weakening. Furthermore, in my apparatus the transverse partition wall 18 may be very thin, 100 105 110

because the pressure on the two faces of the wall balance each other. Hence it is unnecessary to provide stays to prevent the plate from bulging. This effect results from features of my apparatus to be described hereinafter.

At a suitable point on the frame I support a mixing device or mixer 22 which may be of any suitable construction, but preferably such as that shown in Fig. 4 in which the device is in the form of a three-way cock having a cylindrical case 23 of relatively large proportions and capacity and having two threaded nipples 24 for admitting the two liquids into the mixer in the same general direction but in crossing paths. These nipples connect with the tanks respectively by means of suitable pipes 25 and 26. When the plug 27 of the stop cock 22 is in the position shown, the liquids pass into the interior of the plug which provides an enlarged mixing chamber, and mix together to form a foam, and they pass from the mixer by a suitable threaded nipple 28 which carries the mixture forward in the same general direction that the liquids have in entering the mixer. To this nipple is attached a suitable hose 29 for directing the mixture toward the fire. The plug 27 may be rotated by means of an ordinary handle or lever 30.

It is understood that the containers 15 are only partially filled with their respective liquids in order to form air chambers over the liquids. In order to charge the air chambers of these containers with compressed air, I prefer to provide a relatively high pressure compressed air reservoir 31 which may be supported in suitable metal straps 32 on the upper side of the cylinder 16 and preferably at one side. This reservoir 31 is to be charged with compressed air under considerable pressure, and I provide for admitting this air at a reduced pressure into the air chamber in the upper part of each container. For this purpose I prefer to provide a pipe 33 which leads from the reservoir 31 and this pipe is provided with branches 34 which are connected respectively with the two containers 15, connection being made thereto through the upper wall of the cylinder.

Connected in the pipe 33 I provide a reducing valve 34 through which air from the reservoir 31 will pass and develop a reduced pressure in the containers 15. This reducing valve is of any suitable construction which will operate to maintain automatically a substantially continuous pressure in the containers 15. Air is admitted into the reducing valve through a suitable valve 35 when it is desired to use the apparatus.

In Fig. 5 I illustrate a type of pressure-reducing valve which may be employed if desired. In this type of valve the air passes

into the valve at the connection 36 and a small bleeder port 37 leads the high-pressure air upwardly to the upper side of a small valve 38 having a small area exposed to the high pressure. If the pressure is sufficiently high, this valve 38 will be unseated and will move in a downward direction; this will permit the air to pass down into the air chamber 39 and through port 40 into a pilot cylinder 41 in which the air exerts pressure upon a piston 42. This forces the piston 42 downwardly and pushes the valve disk 43 down off of its seat, permitting the air to flow through, and out by way of the pipe connection 44. When the pressure on the side toward which the air is flowing reaches a predetermined point, this pressure exerts itself up through a bleeder port 45 onto the under side of a diaphragm 46 mounted above the air chamber 47. When the pressure in air chamber 47 is sufficiently great, it will raise the diaphragm 46. The diaphragm 46 is attached to the stem or valve 38 so that when it rises, it reseats the valve 38 and shuts off the flow of air whereupon spring 43a closes valve 43. The diaphragm 46 is forced downwardly by a spring 48 the pressure of which may be regulated by means of an adjusting screw 49, carrying a hand wheel 50. Evidently by rotating the hand wheel 50 the degree of pressure developed in the air chamber 47 and in the containers may be nicely regulated. In this way the apparatus can be adjusted so as to change the delivery pressure and the velocity with which the mixture of liquids is projected toward the fire. Evidently, these functions can be adapted to particular requirements depending upon the height of the building on fire or the distance of the point at which the fire is located.

By employing a high-pressure air reservoir such as the reservoir 31, I am enabled to insure that a sufficiently high working pressure will be maintained in the liquid containers until their contents have been entirely consumed. And this effect is attained without the use of unusually large containers or an unusually large high-pressure reservoir.

In order to hold the apparatus in an upright position the handle or shaft 12 is most conveniently provided with a suspended leg 51 which may be allowed to hang in a vertical position. In this way the leg may operate as a stand to hold up the shaft. When the device is being wheeled to the point where the fire is located, this leg may be held up out of the way on a suitable clip 52. The shaft may be provided, if desired, with a small box 53 to hold tools of any kind or hose nozzles, etc.

The arrangement described above for the inlets and outlets of the mixer is highly ad-

vantageous as I produce a thorough mixture of the liquids and effect the exit of the mixture with the same general direction of flow. This prevents the two pressures from the two containers from neutralizing the liquid velocities in the mixer.

The composition of the two solutions I prefer to use with this apparatus is substantially as follows:

10 *Solution No. 1.*

Sodium bi-carbonate-----	8 parts
Water-----	89 "
Foamite (secondary extract of licorice root)-----	3 "

15 *Solution No. 2.*

Aluminum sulfate-----	11 parts
Water-----	89 "

20 The apparatus may include an elevated shelf 54 to be used as a hose-rack to carry a coil of hose.

It is understood that the embodiment of the invention set forth herein is only one of the many embodiments or forms the invention may take, and I do not wish to be limited in the practice of the invention nor in my claims to the particular embodiment set forth. And I may use any feature of my invention without the other features.

What I claim is:

1. A portable fire extinguisher, comprising, in combination, a portable frame, a pair 35 of containers for holding different liquids operating upon mixture to develop a foam and a gas noxious to combustion, a mixer connected with said containers in which the liquids mix to generate the foam and gas, a hose attached to the mixer for projecting the mixture toward the fire, a compressed air reservoir connected with the upper parts of said containers, and an automatic pressure-reducing valve between said reservoir 40 and said containers for maintaining a charge of compressed air in said containers to exert a pressure upon the liquids therein and force the same through said mixer.

2. A portable fire extinguisher, comprising, in combination, a portable frame, a tank having a dividing partition dividing the interior thereof into two containers, said containers for holding different liquids operating upon mixture to develop a foam and a gas noxious to combustion, a mixer connected with said containers in which the liquids mix to generate the foam and gas, a hose attached to the mixer for projecting the mixture toward the fire, a compressed air reservoir, a pipe leading therefrom having branches leading respectively to said containers, and an automatic pressure-reducing valve connected in said pipe for maintaining a charge of compressed air in 55 said containers to exert a pressure upon the

liquids therein and force the same through said mixer.

3. A portable fire-extinguishing apparatus, comprising, in combination, a portable frame, a tank in the form of a cylinder having convex heads, a transverse partition extending across said cylinder and dividing the interior thereof into two containers for holding different liquids operating upon mixture to develop foam and a gas noxious to combustion, a mixer connected with said containers in which the liquids mix to generate foam and a gas, a hose attached to the mixer for projecting the mixture toward the fire, a compressed air reservoir, a pipe leading therefrom having branches leading respectively to said containers, and an automatic pressure-reducing valve connected in said pipe for maintaining a charge of compressed air in said containers above the liquid level therein to exert a pressure upon the liquids and force the same through said mixer.

4. A portable fire-extinguishing apparatus, comprising, in combination, a portable frame, a tank in the form of a cylinder having convex heads, a transverse flat partition extending across said cylinder and dividing the interior thereof into two containers for different liquids operating upon mixture to develop a gas noxious to combustion, a high-pressure air reservoir, an automatic pressure-reducing valve through which air passes from said air reservoir to said containers to develop a working pressure in 100 said containers to force the liquids therefrom, and means for effecting a mixture of the liquids and for directing the same toward the fire.

5. A portable fire-extinguishing apparatus, comprising, in combination, a portable frame, a tank in the form of a cylinder having convex heads, a transverse flat partition extending across said cylinder and dividing the interior thereof into two containers for different liquids operating upon mixture to develop a gas noxious to combustion, a high-pressure air reservoir, an automatic pressure-reducing valve through which air passes from said air reservoir to 105 said containers to develop a working pressure in said containers to force the liquids therefrom, a mixer, pipes leading the liquids from said containers so that they enter said mixer in the same general direction, a delivery nipple on said mixer projecting from the mixer so as to lead the mixture therefrom in the same general direction in which it is admitted to said mixer by said pipes, and a hose attached to said delivery nipple 110 for directing the mixture toward the fire.

6. A portable fire extinguisher, comprising, in combination, a portable frame, a pair of containers for holding different liquids operating upon mixture to develop a foam 115

and a gas noxious to combustion, a mixer having pipe connections with said containers in which the liquids mix to generate a foam and gas, said mixer embodying a 3-way valve, a hose attached to the outlet way of said mixer for projecting the mixture toward the fire, a compressed air reservoir having pipe connections with the said containers, and a pressure-reducing valve in 10 the pipe connections between the reservoir and said containers.

7. A portable fire extinguisher, comprising, in combination, a wheeled frame, a pair of containers for holding different liquids 15 operating upon mixture to develop a foam,

a 3-way valve having an outlet and separate pipe connections with said containers, said valve including in its construction an enlarged mixing chamber in which the liquids mix to generate a foam, and a hose attached 20 to the valve outlet for projecting the foam from the mixing chamber toward the fire.

In testimony whereof I have hereunto set my hand in presence of two subscribing witnesses.

WILLIAM W. WALKER.
